UNITED STATES PATENT OFFICE.

PAUL JOSEPH LAPHAM, OF IONIA, MICHIGAN, ASSIGNOR TO HIMSELF AND SAMUEL M. FARGO, OF CHICAGO, ILLINOIS.

HEEL BURNISHING AND MILLING MACHINE.

SPECIFICATION forming part of Letters Patent No. 291,608, dated January 8, 1884.

Application filed October 20, 1883. (No model.)

To all whom it may concern:

Be it known that I, PAUL J. LAPHAM, a citizen of the United States, residing in Ionia, in the county of Ionia and State of Michigan, 5 have invented a new and useful Improvement in Heel-Burnishing and Milling or Beading Machines, of which the following is a specification.

This invention relates to a combined boot or 10 shoe heel burnishing and heel-seat beading or milling machine.

The object of the invention is to provide a 15 machine for not only burnishing the heel, but also for milling, beading, or otherwise ornamenting the heel-seat or the base of the heel between the heel proper and the quarter or counter.

The object of the invention is also to so combine the heel-seat milling or beading device 20 or mechanism with the burnishing-machine, that the former may be readily and conveniently attached or applied to ordinary burnishing-machines already in use.

In my invention the milling or beading tool 25 is mounted on or secured to a jointed slide, the joint in the slide permitting the tool as it is revolved around the heel to follow the heel-seat, the tool being guided by a lip, which fits in the groove or crease between the heel-seat 30 and counter. This jointed slide is itself mounted movably on the burnishing-tool, so as to revolve with it around the heel, and mechanism is provided for moving the slide, so as to project its milling or other tool beyond the 35 polishing-surface of the burnishing-tool, and thus pressing said tool against the heel-seat to mill, bead, or otherwise ornament the same.

In the accompanying drawings, which form a part of this specification, and in which similar letters of reference indicate like parts, Figure 1 is a side elevation of a device embodying my invention. Fig. 2 is an enlarged or full-sized front view of the burnishing-tool and the jointed slide mounted thereon. Fig. 45 3 is a plan view of the machine. Fig. 4 is a central vertical longitudinal section taken on line 4 4 of Fig. 2. Fig. 5 is a detail sectional view of the jointed slide on line 5 5 of Fig. 1.

Fig. 6 is a section of the handle and rack on line 6 6 of Fig. 3.

50

In the drawings, A is the frame or pedestal of the machine, upon which the rock-shaft A' is journaled in suitable bearings, and to which shaft the rotary pivoted tool-carrier arm B is secured, so as to rock or swing with said shaft around the heel of the boot or shoe. The tool-carrier arm B is hinged or pivoted by means of a bolt, b, to a projection, b', on the sleeve B', which sleeve is rigidly secured to the rock-shaft A' by a set-screw or other suitable means. 55

C is the burnishing-tool pivoted on the end of the carrier-arm by a bolt, c, and held in position by a spring, c', which is bolted to the carrier-arm, and the end of which abuts against the rear part of the burnishing-tool. The carrier-arm B is oscillated or turned on its pivot b, so as to continually press the burnishing-tool against the heel as it swings around the same by means of a spring, C', one end of which is secured by a bolt, c'', to a flange, c', on the 60 sleeve B', and the other end of which rests on a roller, c'', mounted in the slotted bracket C'', which is suspended from and bolted to the tool-carrier arm. 65

C' is a set-screw, the end of which projects 70 against the rock-shaft, and which serves to limit the pivotal or vibratory motion of the tool-carrier arm.

D D' is a two-part or jointed slide, the upper one of which, D, is provided with tongues 80 or guides d on its edges, which fit in corresponding guideways or grooves, d', cut in the projecting ledges d'' on the front end of the burnishing-tool C. The lower or tool-holding part, D', of the jointed slide is made narrow enough 85 to fit between the ledges d'', so as to permit of its pivotal motion on the upper slide, D, and it is provided with a curved lip, d'', adapted to project into the crease or groove a between the heel-seat and counter of the shoe or boot. 90 The tool-holder D', being pivoted freely to the slide D, permits the lip d'' to follow the said crease or groove as it swings around the heel, and thus causes the milling or other tool mounted on said holder D' to accurately follow the heel-seat. The outer face, d', of the 95

lip d^3 is curved to conform to the counter of the shoe. The tool-holder D' is provided with a vertical slot, d^5 , in which is mounted a milling or other tool, d^6 . The pin or pivot d^7 , on which the wheel d^6 turns or revolves, is riveted or secured rigidly to an adjustable plate, d^8 , which is attached to the holder D' by a screw, d^9 , that passes through a slot, d^{10} , in said plate, so that the milling wheel or tool may be readily adjusted and quickly changed for another tool when desired. The pin d^7 fits loosely in a slot, d^{11} , in the tool-holder D', so as to permit of this adjustment. The tool-holder D' is hinged to the slide D by a pin, d^{12} , secured rigidly in the lug d^{13} on the holder D', and which pin fits in grooves or slots d^{14} in the ears d^{15} on the slide D. A spring, d^{16} , is secured to the slide D by a screw, d^{17} , and a pin, d^{18} , and it is provided at its other end with a slot, d^{19} , through which projects a pin, d^{20} , secured to the holder D'. This spring serves to hold the pivoted tool-holder D' in position, and at the same time allow it to yield or turn on its pivot when necessary, and the slot d^{19} and pin d^{20} also operate to limit its pivotal motion as well as to support the holder D' or connect it to the slide D. By this means of pivoting or connecting the tool-holder D' to the slide D the former may be very readily removed from the slide and replaced by another, as all that is required to be done to remove it is to slightly loosen the screw d^{17} , when the pin d^{20} may be disengaged from the slot d^{19} .

In addition to the milling tool or wheel d^6 I ordinarily provide the tool-holder D' with a raised projection or beading-tool, d^{21} , at the base of the lip d^3 , on the inside thereof, which serves to curve or round off the upper edge or corner of the heel-seat; and the tool-holder D' may of course be provided with other tools or devices for ornamenting the heel-seat of the shoe or boot, and they may be made either integral with the holder D' or movably or rigidly mounted thereon.

The slide D is reciprocated vertically in the burnishing-tool C, so as to press or hold the milling or other tool against the heel-seat by means of a reciprocating wedge, E, provided with an inclined dovetail or guide, e, which fits in a corresponding dovetail groove or way, e' , on the slide D, so that the horizontal movement of the wedge will impart a vertical movement to the slide D and to the tool-holder D', pivoted to said slide. The wedge E reciprocates between the ledges or projecting flanges or faces d^2 , and is provided with flanges or guides e^2 , which rest or slide on the pins or projections e^3 on the projecting sides d^2 of the burnishing-tool. The burnishing-tool is made hollow, so that the wedge E may reciprocate or be confined inside the same, and thus present a neater and more compact appearance. The wedge is confined on its top by a cap-piece, e^4 , secured by screws e^5 to the projecting ledges or sides d^2 . The bottom face, e^6 , of the

wedge, fitting on the inclined end e^7 of the slide D, serves to force said slide down, the dovetails e and e' serving simply to raise the slide. Its reciprocating movement is imparted to the wedge E from the handle or lever F, which is pivoted to the frame A by means of the forked rack-bar G, collar H, and connecting-bar K. The lever F is provided with a toothed segment, f, and it is pivoted to the cap-bolt, f' , which secures the cap f^2 to the frame A, the lever being provided with a brass bushing or collar, f^3 , which surrounds the bolt and prevents the lever from coming in contact with the threads or rough surface of the bolt. A washer, f^4 , fits on top of the lever. The rack-bar G reciprocates on the cap f^2 , the rack-bar being provided with a slot, g , through which projects a guide-block, g' , which is secured to the cap f^2 by means of screws or pins g^2 , and a cap-plate, g^3 , the edges of which project over the rack-bar, so as to hold it down. The rack-bar is also provided with a yoke, g^4 , which engages with a groove, h , in the collar H. The collar H fits loosely on the shaft A', and is provided with an arm, h' , having an inclined slot, h^2 , therein. The connecting-bar K reciprocates on the top face of the tool-carrier arm B, its motion being guided by a flat-sided screw, k, secured to the arm B, and which fits in a slot, k' , in the connecting-bar, and by a bent cap, k^2 , fitting over the connecting-bar, and which is also secured to the arm B by means of the screws k^3 . The connecting-bar K is pivoted or jointed to the wedge E by a pin, k^4 , so as to permit of and not interfere with the vibratory motion of the burnishing-tool C on its pivot c. A pin, k^5 , passes through a hole in the end of the connecting-bar K, and through the slot h^2 in the collar-arm h' , thus connecting said bar to the collar H. The function of the slot h^2 is to permit of the vibratory movement of the arm B on its pivot b, and to compensate for the end-thrust consequent thereto, or longitudinal movement that would otherwise be imparted to the collar H on the shaft A'. This slot should be cut in the arc of a circle whose center is the pivot of the arm B. By making the connection between the rack-bar F and the connecting-bar K by means of the collar H on the shaft A', the swinging movement of the vibratory arm B around said shaft is freely permitted. The connecting-bar K is divided or slotted at K' , so as to embrace the adjusting-screw C³.

All that is required to apply my invention to any ordinary burnishing-machine is simply to slip the collar H on the shaft A', remove the cap-bolt f' , and attach the lever F, mount the rack-bar G on the cap f^2 , and the connecting-bar K on the vibratory arm B, and make guideways in the burnishing-tool for the slide D.

The jack for holding the shoe or boot I have not herein shown, as any ordinary jacking device may be used.

What I claim is—

1. The combination, with a heel-burnishing tool, of a reciprocating slide mounted thereon, and provided with a heel-seat milling or other tool, and suitable actuating means, substantially as specified.
2. The combination, with a heel-burnishing tool, of a reciprocating jointed slide mounted thereon, and provided with a milling or other tool, substantially as specified.
- 10 3. The combination, with a heel-burnishing tool, of a reciprocating slide mounted thereon, and a reciprocating slide or tool-holder pivoted thereto, and provided with a lip adapted to follow the crease or groove between the heel-seat and counter of the shoe, and a heel-seat milling or other tool, substantially as specified.
- 15 4. The combination, with a heel-burnishing tool, of a reciprocating slide mounted thereon, a reciprocating slide or tool-holder pivoted to said slide, and provided with a heel-seat beading-tool, a heel-seat milling-wheel, and a lip adapted to follow the groove between the heel-seat and counter of the shoe, substantially as specified.
- 20 5. The combination, with a heel-burnishing tool, of a reciprocating slide mounted thereon, a tool-holder pivoted to said slide and provided with a milling or other tool, and a device for reciprocating said slide, also mounted on said burnishing tool, and suitable actuating means, substantially as specified.
- 25 6. The combination, with a heel-burnishing tool, of a reciprocating slide mounted thereon, a tool-holder pivoted to said slide and provided with a heel-seat milling or other tool, and a reciprocating wedge mounted on said burnishing tool for operating said slide, substantially as specified.
- 30 7. The combination of a swinging vibratory tool-carrier arm with a reciprocating slide mounted in a block pivoted to said arm, a tool-holder pivoted to said slide, and provided with a lip adapted to follow the groove between the heel-seat and counter of the shoe, and provided also with a heel-seat-ornamenting tool, and a device, substantially as described, for reciprocating said slide, also mounted on said pivoted block, substantially as specified.
- 35 8. The combination, with a swinging vibratory tool-carrier arm, of a reciprocating slide mounted in a block pivoted to said arm, and provided with a heel-seat milling or other tool, substantially as specified.
- 40 9. The combination of the slide D and tool-holder D', pivoted thereto, and provided with a lip adapted to follow the groove between the heel seat and counter of the shoe, and with a heel-seat-ornamenting tool and a spring-connection between said tool-holder and slide, substantially as specified.
- 45 10. The combination, with the slide D, of the tool-holder D', pivoted thereto, and provided with lip d³ and a heel-seat milling or other tool, and a spring secured to said slide, and
- provided with a slot which engages a pin secured to said tool-holder, substantially as specified.
11. The combination, with the slide D, of the tool-holder D', pivoted thereto, and provided with lip d³ and a heel-seat milling or other tool, and a reciprocating wedge E, provided with dovetails or grooves engaging with corresponding dovetails or grooves in the end of said slides, to reciprocate the same, substantially as specified.
12. The combination, with a heel-burnishing tool, of a swinging vibratory tool-carrier arm, a heel-seat-ornamenting tool mounted movably on said arm, and mechanism for operating the same, consisting of a connecting-bar reciprocating on said arm, and attached to a collar on the rock-shaft of the machine, said collar having a swivel-connection with the actuating lever or device, substantially as specified.
13. The combination, in a heel-burnishing and heel-seat milling or ornamenting machine, of the rock-shaft and the swinging vibratory tool-carrier arm with a sliding collar on the rock-shaft, connected with the mechanism for communicating motion to the heel-seat milling or ornamenting tool and with the operating lever or device, one of said connections being a swivel-connection, substantially as specified.
14. The combination, with swinging vibratory arm B and rock-shaft A', of connecting-bar K, reciprocating on said arm B, collar H, provided with an arm, h', having slot h², for connecting the same with said bar K, rack-bar G, provided with yoke g¹, fitting in groove h² of said collar, and segment-lever F, pivoted to the frame of the machine, substantially as specified.
15. The combination of the rack-bar G, provided with slot g, with the guide-block g', secured to the cap f², on which said rack-bar reciprocates, substantially as specified.
16. The combination of rack-bar G with lever F, provided with toothed segment f, bolt f', and bushing or collar f³, surrounding said bolt, to form a bearing for said lever, substantially as specified.
17. The combination of shaft A' with swinging vibratory tool-carrier arm B, a connecting-bar, K, reciprocating thereon, and a collar, H, adapted to slide on said shaft A, and having a slotted connection with said bar K, to permit of the vibratory movement of the carrier-arm B, substantially as specified.
18. A hollow heel-burnishing tool mounted on a swinging vibratory tool-carrier arm, and provided with a heel-seat milling or other tool having a reciprocating and pivotal or vibratory movement thereon, substantially as specified.
19. The combination, with a heel-burnishing tool pivoted to a swinging vibratory tool-carrier arm, of a reciprocating slide mounted on said burnishing tool, and provided with a heel-seat-ornamenting tool, a device for reciprocating said slide, also mounted on said burnishing tool, and a slot which engages a pin secured to said tool-holder, substantially as specified.

nishing-tool, an operating-lever pivoted on the stationary frame of the machine, and connecting mechanism from said lever to said device, for reciprocating said slide, substantially as specified.

20. The combination of rock-shaft A' with vibratory swinging tool-carrier arm B, bur-

nishing-tool C, pivoted thereto, reciprocating slide D, mounted on said tool C, reciprocating to wedge E, also mounted on said tool C, con-

necting-bar K, adapted to slide on said arm B, collar H, adapted to slide on said shaft A', rack-bar G, adapted to slide on said frame A, and a lever, F, for operating the same, substantially as specified.

Chicago, Illinois, October 15, A. D. 1883.
